UNITED STATES PATENT OFFICE

ELMER PITCHER, OF MINNEAPOLIS, MINNESOTA, ASSIGNOR, BY MESNE ASSIGNMENTS, TO M. T. NAGLE, OF ST. PAUL, MINNESOTA, J. R. SCHOFFMAN, OF ST. JAMES, MINNESOTA, CHARLES H. MILLER, OF PORTLAND, OREGON, ELMER PITCHER, OF MINNEAPOLIS, MINNESOTA, J. L. MOORE, OF WIMBLEDON, NORTH DAKOTA, ALBERT RUNNING, OF ST. JAMES, MINNESOTA, AND MYLES HENDERSON, OF CROSBY, NORTH DAKOTA

SNOWPLOW

Application filed March 23, 1928. Serial No. 264,188.

My present invention has for its object to provide a highly efficient snow plow, by the use of which snow may be very quickly and easily removed from city and village streets and highways with the least possible interference with traffic and at a comparatively small cost.

To the above end, generally stated, the invention consists of the novel devices and combinations of devices hereinafter described and defined in the claim.

Snow plows now generally used, scrape or push snow from a roadbed to the sides thereof and the width to which the roadbed can thus be cleared of snow is limited and at the same time the snow is banked at the sides of the roadbed, which snow soon freezes and turns to ice and if removed, picks and shovels must be used. These banks of snow interfere with the clearing of the roadbed during succeeding snows and as such snows are scraped or pushed to the sides of the roadbed the banks increase in width, thus narrowing up the roadbed to such an extent as to interfere 25 with traffic. Furthermore, these banks of snow prevent natural drainage of the roadbed with a result that during thaws and rains, water often accumulates on the roadbed to such an extent as to interfere with traffic and also cause deep mud on dirt or gravel-surfaced roadbeds and thereby causes the same to disintegrate during use.

By the use of my improved snow plow, a roadbed may be cleared of snow its full width without building up banks at the sides thereof or interfering with the natural drainage. This clearing of a dirt or gravel roadbed to its full width particularly after a heavy snow is highly important in order to permit the ground to freeze for the reason that frost in the ground prevents the roadbed from disintegrating during thaws and rains particularly when traffic is heavy and the roadbed is used by busses, trucks or other heavy vehicles.

In the accompanying drawings, which illustrate the invention, like characters indicate like parts throughout the several views. Referring to the drawings:

Fig. 1 is a plan view of the improved snow plow;

Fig. 2 is a right side elevation of the same;

Fig. 3 is a view corresponding to Fig. 1, with some parts removed and other parts shown in horizontal section;

Fig. 4 is an enlarged fragmentary detail view partly in right side elevation and partly in longitudinal central section showing the front end portion of the machine;

Fig. 5 is a fragmentary detail view principally in section taken on the line 5—5 of Fig. 1, on an enlarged scale;

Fig. 6 is a view partly in front elevation and partly in section taken on the line 6—6 of Fig. 3;

Fig. 7 is a transverse vertical section taken on the line 7—7 of Fig. 2;

Fig. 8 is a plan view of the fan;

Fig. 9 is an edge elevation of the same; and

Fig. 10 is a transverse vertical section taken substantially on the line 10—10 of Fig. 1 and further illustrating deflecting hoods for the discharge chutes.

The improved snow plow, as shown, includes a self-propelled truck in the form of a tractor having a long main frame 11 supported on a pair of rear traction wheels 12 and a pair of front steering wheels 13. An internal combustion engine 14 for propelling the machine is mounted on the rear end portion of the frame 11 with suitable driving connections to the traction wheels 12, but for the purpose of this case, it is not thought necessary to illustrate the same. Also mounted on the frame 11 at the rear of the engine 14 is a cab 15 for the operator of the machine. Steering mechanism for the front wheels 13 is indicated as an entirety by the numeral 16 with the exception of a steering wheel 17 within the cab 15. Rigidly secured to the front end portion of the main frame 11 is a supplemental frame 18 which materially increases the width of said main frame.

Overlying and extending forward of the main frame 11 and supplemental frame 18 is a rearwardly inclined deck 19 preferably made of wood to prevent snow from sticking thereto. This deck 19 is supported on a pair of

longitudinally extended channel side bars 20 and an intermediate I-bar 21. A long upper transverse shaft 22 is journaled in a pair of transversely aligned bearings 23. These bearings 23 have long diverging legs 24 rigidly secured to the side members of the supplemental frame 18 and support the shaft 22 materially above said supplemental frame.

The bars 20 and 21 are pivoted on the shaft 22 at their rear ends and support the deck 19 with freedom for vertical swinging movement longitudinally of the machine. A long transverse shaft 25 which extends parallel to the shaft 22 is journaled in the front or lower end portions of the bars 20 and 21. Longitudinally extensible braces limit the rearward movement of the lower end of the deck 19 toward the machine and each thereof comprises a tubular member 26, pivoted at 27 to the supplemental frame, and a rod 28 telescoped therein and pivoted on the shaft 25.

Normally, the brace rods 28 engage the inner ends of the tubular brace members 26 as stops to limit the movement of the lower or front end of the deck 19 toward the machine and afford a rigid support therefor.

A rearwardly inclined metal blade 29 extends transversely of the machine at the lower end of the deck 19 and has a relatively sharp lower cutting edge. This blade 29 is secured to a pair of runners 30, which, in turn, are rigidly secured to the lower ends of the bars 20. These runners 30 are provided with road-engaging shoes 31, the forward ends of which are rigidly secured thereto. Said shoes 31 are also intermediately secured to the runners 30 by longitudinally adjustable posts 32. These posts 32 may take various different forms, for instance, they may have right and left-hand threaded engagement with the runners 30 and shoes 31. By longitudinally adjusting the posts 32, the shoes 31 may be adjusted to raise or lower the cutting edge of the blade 29 in respect to a roadbed. Said shoes have sufficient flexibility to permit springing movement thereof at their front ends during the adjustment of the posts 32. By adjusting the shoes 31, the cutter blade 29 may be set different distances above the roadbed so as to scrape substantially all of the snow or ice therefrom or leave sufficient snow on the roadbed for bob sleds and sleighs.

As previously stated, the deck 19 at its upper end is pivoted to the shaft 22 for vertical swinging movement and its lower end is held by counterbalancing devices, each of which comprises a lever 33, in the form of a bell-crank having a long arm and a short arm, and a coiled spring 34. The levers 33 are pivoted at their elbows to the supplemental frame 18 and their long arms extend horizontally forward and are connected to the deck bars 20 by headed studs 35 which extend through longitudinal slots 36 in said arms. The short arms of the levers 33 extend up-

ward and one end of the springs 34 are attached thereto and the other ends of said springs are anchored to the rear legs 24. The tension of the springs 34 is such that normally the brace rods 28 engage the inner ends of the tubular brace members 26 as stops but hold the deck 19 so that very little power is required to lift the front end thereof and raise the cutter blade 29 and at which time the rods 28 move outward in respect to the tubular brace members 26 in which they are mounted.

To lift the front end of the deck 19 and hold the same raised, there is provided a pair of forwardly projecting lifting levers 37 rigidly secured to a transverse rock shaft 38 mounted in bearings in the main frame 11. These levers 37 have at their free ends fixed studs 39 which extend under and engage the lower longitudinal edges of the long arms of the levers 33. The right-hand lifting lever 37 is provided with an upstanding crank-acting extension 40 to which the front end of a long operating rod 41 is pivotally attached. The rear or other end of the operating rod 41 is pivoted to a latch lever 42 within the cab 15 and co-operating with said lever is a latch segment 43 for holding said lever where set.

Obviously, by drawing rearward on the latch lever 42, the levers 37 may be operated by the connections just described to lift the long arms of the levers 33 and thereby raise the forward end of the deck 19. It may be here stated that the rock shaft 38 forms the pivot on which the levers 33 are mounted and that the bar 21 forms a brace between the shafts 22 and 25.

Mounted to travel upwardly over the deck 19 is a combined pick-up and elevator comprising two edgewise spaced sections. Each of said sections comprises three belts 44, in the form of sprocket chains which run over sprocket wheels 45 on the shafts 22 and 25, and slats or blades 46 in the form of metal bars set vertically edgewise perpendicular to said belts and rigidly secured to certain of the links thereof. The upwardly moving sections of the combined pick-up and elevator travel upward on the upper face of the deck 19 and the downwardly moving sections thereof pass under said deck.

Outwardly diverging side boards 47 are secured to the deck 19 at the outer longitudinal edges of the combined pick-up and elevator and it is important to note that during the return movement of the combined pick-up and elevator the slats 46 in passing around the sprocket wheels 45 are covered by the cutter blade 29 and thereby protected from the weight of the snow until they assume a substantially perpendicular position to the deck 19 and are supported thereby.

The combined pick-up and elevator is driven at the proper speed from an internal

combustion engine mounted on the main frame 11 just forward of the tractor engine 14 and indicated as an entirety by the numeral 48, with the exception of a sprocket 5 wheel 49 on its crank shaft. The driving connections from the engine 48 to the shaft 22 from which the combined pick-up and elevator is operated include a long sprocket chain 50 which runs over the sprocket wheel 49 and 10 a relatively small sprocket wheel 51 mounted on a shaft 52 journaled in a bearing 53 on the main frame 11. Said connections further include a sprocket chain 54 which runs over a relatively small sprocket wheel 55 on the 15 shaft 52 and a relatively large sprocket wheel 56 on the shaft 22.

From the above description it is evident that the cutter blade 29 will direct snow onto the deck 19 with a shovel action and its sharp 20 lower edge will cut ice or packed or frozen snow. Snow directed onto the deck 19 by the cutter blade 29 is carried upward thereon by the slats or blades 46 and precipitated from the raised rear end of said deck into 25 the open top of the fan 57 having a closed bottom.

The fan 57 is rigidly secured to the upper end of a short shaft 58. This shaft 58 is journaled in bearings in a gear housing 59 in 30 a slightly forwardly inclined position so that the fan 57 rotates in a plane that is inclined in the same direction as the deck 19 but at a much less degree. Said fan 57 is mounted in an open top fan housing 60 which in turn 35 is mounted on the gear housing 59 and rigidly secured thereto. The fan housing 60 is further supported and rigidly held by a rearwardly extended arm 61 on the gear housing 59. It is important to note that snow from 40 the deck 19 will be precipitated from the deck 19 into the fan 57 through its open top rearward of the shaft 58 and onto the closed bottom of said fan where it is held to be discharged, as will presently appear.

45 A discharge chute 62 leads from the fan housing 60 at each side of the machine in a slightly rearwardly and upwardly inclined position. These discharge chutes 62 are located rearward of the axis of the fan 57 and 50 extend substantially in radial lines projected from the axis of the fan 57 so that when the blades of the fan are aligned with said discharge chutes, they let go of the snow which is discharged outward through the chutes 62 55 in a direct line with said blades.

A gathering plate 63 extends from one discharge chute 62 to the other at the rear of the fan housing 60 and to a height considerably above the rear end of the deck 19 to 60 gather snow precipitated from the deck 19 and direct the same into the open top of the fan 57. For each discharge chute 62 is a gate 64 hinged at the bottom of said chute for 65 swinging movement from an upright operative position to an inoperative position and

in which it projects outwardly on the bottom of said chute. The gates 64 are alternately opened and closed by means of a hand wheel 65 in the cab 15. This hand wheel 65 is secured to the rear end of an operating rod 70 journaled in a bearing in the front wall of the cab 15 and in a bearing 67 on the main frame 11. On the front end of the operating rod 66 is a crank arm 68 connected by a link 69 to a crosstie rod 70 which connects a pair 75 of depending arms 71 on the gates 64, as best shown in Fig. 10.

The fan 57 is driven in the direction of the arrow indicated in Fig. 1 from the shaft 52 which projects into the gear housing 59. In addition to the bearing 53 the shaft 52 is also journaled in a bearing on the gear housing 59 and has on its inner end a bevel pinion 72 which meshes with a bevel gear 73 on the fan shaft 58.

Normally, snow is discharged from the fan 57 through the right-hand chute 62, but in case of a strong wind or when passing by a farm house or other building or a cross-road the snow may be discharged through the left-hand chute 62. Snow, when discharged through the right-hand chute 62 is carried a very short distance by the fan 57 but when discharged through the left-hand chute 62 it must be carried a much longer distance by 95 said fan. The upper longitudinal edge portions of the blades of the fan 57 are curved forwardly in the direction of the rotation of said fan and produce a suction which draws the snow thereagainst under the rotation of 100 the fan 57 and holds the snow where the same is thrown from the blades of said fan longitudinally thereof through the right-hand discharge chute 62.

When snow is discharged through the left-hand chute 62 sufficient pressure is produced thereon in the housing 60 by the fan 57 to cause its discharge through said left-hand chute 62.

At the outer end of each discharge chute 62 110 is a deflecting hood 74. These deflecting hoods 74 are hinged to the upper outer end portions of the chutes 62 and are curved outwardly and downwardly therefrom and intermediately connected by longitudinally extensible braces 75 to the bottoms of said discharge chutes. Each brace 75 comprises a pair of threaded rods connected by a turn buckle 76 and pivoted the one to the respective hood 74 and the other to the respective 115 discharge chute 62. The deflecting hoods 74 are used only when the machine is operating on a village or city street where it is desirable to carry the snow directly downward and deposit the same at the curb or gutter. When 120 the machine is operating on a highway, the deflecting hoods 74 are removed so that the snow will be discharged at a considerable distance from the highway.

On the upper face of the deck 19 are metal 130

wearing strips 77 for the combined pick-up and elevator.

The operation of the above described machine may be briefly described as follows:

5 The tractor and the combined pick-up and elevator are independently operated by the respective engines 14 and 48 thus permitting said combined pick-up and elevator to be operated at a constant speed depending on the
10 amount of snow the machine has to handle.

During the forward travel of the machine, the combined pick-up and elevator is fed obliquely into the snow by the tractor and the blade 29 picks up the snow on the surface
15 of the roadbed, and cuts any ice or frozen snow in the path thereof and delivers the snow onto the deck 19. The snow carried upward on the deck 19 by the combined pick-up and elevator is precipitated into the fan 57 and
20 is discharged thereby through one of the chutes 62. The force with which the snow is discharged through either one of the chutes 62 is sufficient to carry the same well outward of the roadbed so as not to form a bank at the
25 side thereof. By picking up the snow from the roadbed and delivering the same to one side thereof, the roadbed may be cleared to any desired width and without interfering with the natural drainage.

30 What I claim is:

In a machine of the class described, the combination with a truck, of a forwardly inclined deck mounted to swing about a horizontal axis, a scraper blade at the receiving
35 end of said deck, a counterbalancing device for said deck, a lifting device for swinging said deck about said horizontal axis to raise the scraper blade, and a brace normally holding said deck with the scraper blade in an
40 operative position with freedom for lifting movement.

In testimony whereof I affix my signature.

ELMER PITCHER.
